UNITED STATES PATENT OFFICE

105,159

DESIGN FOR A SHOE CLEAT

Frank Wilcox, Los Angeles, Calif.

Application August 4, 1936, Serial No. 64,230

Term of patent 14 years

To all whom it may concern:

Be it known that I, Frank Wilcox, a citizen of the United States, residing at Los Angeles, in the county of Los Angeles and State of California, have invented a new, original, and ornamental Design for Shoe Cleat, of which the following is a specification, reference being had to the accompanying drawing, forming part thereof, in which

Fig. 1 is an elevational view of a shoe cleat showing my new design;

Fig. 2 is a plan view of the design shown in Fig. 1;

Fig. 3 is a fragmentary sectional view taken along the line 3—3 of Fig. 2; and

Fig. 4 is another fragmentary sectional view taken along the line 4—4 of Fig. 2.

The shoe cleat has a concave conical portion which terminates at the base in a vertical wall. An annular shelf extends outwardly from the wall and terminates in a second vertical wall. Formed integral with the cleat are four rounded projections which extend upwardly from the annular shelf to a point slightly above the meeting point of the conical portion of the cleat and the first mentioned vertical wall. Each of these projections terminates in a flat upper surface and has a rounded outer surface.

I claim:

The ornamental design for shoe cleat as shown and described.

FRANK WILCOX.
